UNITED STATES PATENT OFFICE.

JOSEPH WIESENFIELD, OF BALTIMORE, MARYLAND; HATTIE M. WIESENFIELD EXECUTRIX OF SAID JOSEPH WIESENFIELD, DECEASED.

SADDLE GIRTH.

Application filed November 18, 1926. Serial No. 149,058.

This invention relates to improvements in the structure of saddle girths, whereby the girth is provided with an elastic portion and a protecting sheath for said portion. It is well known that in saddling horses, the horse will sometimes distend his body while the girth is being applied, and then relax his body, leaving the girth loose. To compensate for this occurrence, the 10 saddle girth of my invention is made with an elastic strip at one end which will stretch if the horse expands his body, and contract afterwards, leaving the girth close fitting. As the elastic strip would soon deteriorate and lose its elasticity if exposed to the weather and to the perspiration from the horse's body, I provide a leather sheath which encloses this strip, this sheath being secured to the outer end of the elastic strip 15 and extending telescopically over the adjacent end of the leather band which forms the body of the girth, so that with the stretching and relaxing of the elastic strip the sheath may adjust itself along the band. 20 In the accompanying drawing, Fig. 1 is a perspective view of a girth provided with my improvements, the sheath for the elastic strip being shown partly opened; Fig. 2 is a plan view of the outer side of the end of the girth having the elastic strip; Fig. 3 is a section on the line 3—3 of Fig. 2; Fig. 4 is a section on the line 4—4 of Fig. 2; and, Fig. 5 is a similar section, on a larger scale, than that in Fig. 4. Referring to the drawing, *a* represents a 25 leather band composing the main portion of the girth, and *b* indicates a strip of elastic fabric, attached to one end of the leather band. This strip is protected by a leather sheath *c*, which is secured to the free end of the strip and extends around the strip and over the adjacent end of the band *a*. The sheath is not secured to the band, but is slideable telescopically upon it so that it may lie smoothly against the band 30 and slide thereon when the elastic strip is stretched and relaxed.

Referring more in detail to the structure, the leather band *a* is folded longitudinally into three folds, *a'*, *a''*, and *a'''*, and the elastic fabric is secured between the folds 55 *a''* and *a'''*. The elastic strip comprises a part *b'*, having its side edges 1 turned inwardly, and a similar part *b''*, having its side edges 2 turned inwardly, and these parts and their inwardly turned ends are 60 stitched together and to the folds of the leather band by rows of stitches 3 and 4. Thus, as shown in Figs. 4 and 5, the elastic strip has four folds at its sides stitched together and to the leather band. The elastic 65 band is therefore very strong and has a strong connection with the leather.

The sheath *c*, composed of a piece of pliable leather, is folded around the elastic strip and the edges of the sheath are 70 stitched together, as shown at 5. The sheath extends slightly beyond the end of the elastic strip, so as to entirely enclose the latter. Straps 6 are doubled over the end of the strip and secured to the elastic 75 strip and to the sheath and carry buckles 7 for attachment to the saddle straps. As shown, each strap 6 has one end 6^a, on the inner side of the girth, arranged beneath the sheath, and the other end 6^b, on the 80 outer side of the girth, extending over the sheath, and these two ends are stitched together through the four folds of the elastic fabric, making a strong connection between the straps and the fabric. The opposite 85 end of the girth has buckles 8 secured thereto by straps 9.

It will be evident from the foregoing description that when the girth is applied to a horse, the elastic section of the girth 90 will cause the latter to closely fit the horse under all conditions. The sheath being secured to the strip and fitting telescopically on the leather band of the girth, will adjust itself on the leather when the elastic strip 95 is stretched or relaxed, and this sheath will protect the elastic strip from the weather and from the perspiration from the body of the horse.

What I claim is:

A saddle girth comprising a longitudinally folded leather band, a strip of elastic

material secured at one of its ends to one end of said band and between the folds thereof, a sheath of pliable material covering said strip and secured to its free end, 5 said sheath extending over the adjacent end portion of the band and being slidable thereon, and buckle straps doubled over

the end of the strip and secured to the strip and sheath, one end of each strap, at the inner side of the girth, being enclosed 10 by the sheath.

In testimony whereof I hereunto affix my signature.

JOSEPH WIESENFELD.
